UNITED STATES PATENT OFFICE.

EDGAR K. BETTS, OF LANSINGBURG, NEW YORK, ASSIGNOR TO EARL & WILSON, OF TROY, NEW YORK.

DESIGN FOR A DISPLAY-CARD FOR SHIRTS.

SPECIFICATION forming part of Design No. 30,513, dated April 4, 1899.

Application filed December 27, 1898. Serial No. 700,457. Term of patent 14 years.

To all whom it may concern:

Be it known that I, EDGAR K. BETTS, a citizen of the United States, residing at the village of Lansingburg, county of Rensselaer, 5 and State of New York, have invented and produced a new and original Design for a Display-Card for Shirts, of which the following is a full description, reference being had to the accompanying drawings, wherein—

10 Figure 1 represents a face view of a display-card embodying my new design, and Fig. 2 is a central longitudinal section of the same.

The design consists in the ornamental configuration of the display-card.

15 The card is of oblong generally rectangular form, having its side edges A A' and one end edge A² defined by straight lines. The other end edge of the card is defined by the curved lines B, B', and B², forming in the middle of such end the segmental indentation C, lying between the corner projections C' C², the ends of which are slightly convexed and defined by the curved lines B B', whereby 20 the curved lines form a circular swell, with a comparatively small segmental indentation in the middle of the swell. The card is also provided with an ornamental shield-shaped figure D, located just below the segmental indentation C, the upper edge D' of such figure being formed by a curved line concentric with 30 the curved line B², which borders said indentation.

The leading feature of the design consists in the display-card, oblong and generally rectangular in shape, having one end in the form 35 of a circular swell, with a comparatively small segmental indentation in the middle of the swell.

What I claim as new, and desire to secure by Letters Patent, is—40 The design for a display-card for shirts herein shown and described.

In testimony whereof I have hereunto set my hand this 20th day of December, 1898.

EDGAR K. BETTS.
